FLORAL RACK

Filed Nov. 21, 1929

UNITED STATES PATENT OFFICE

JOHN G. TURNER, OF PUEBLO, COLORADO

FLORAL RACK

Application filed November 21, 1929. Serial No. 408,873.

This invention relates to an improved floral rack or stand designed particularly for use by florists, undertakers and funeral directors in supporting floral pieces in funeral parlors and susceptible of general commercial use for supporting and displaying flowers in churches, auditoriums, homes, and the like.

An object is to provide a simple and economical device which is inconspicuous and capable of being readily handled and carried in compact form so that it will not present the bulky and clumsy appearances of devices of this general type with which I am familiar.

The further object is to provide a flower rack for the purpose stated so constructed that it may be folded in compact form with the floral piece attached thereto so that it may be carried about in readiness to be placed in display position.

The floral display rack may be used for displaying wreaths, sprays, and other arts and wares of the floral industry. The advantages of the unique features are twofold, first, the hinged floral supporting frame provides a novel display panel susceptible of assuming diversified angular positions thus permitting the flowers to be arranged in a vertical, horizontal or intermediate angular position. Second, the folding properties of the structure permit it to be folded flat for shipping purposes without moving the flowers therefrom. The latter advantage permits the florist to arrange the wreath and spray in an artistic manner and to insure the fact that the wreath or spray to be displayed in the same manner as originally conceived by the artist.

In the drawing:

The single figure represents a perspective view of the complete rack set up for use.

Referring now to the drawing by reference numerals, it will be seen that the principal support is in the nature of a tripod. It comprises a substantially U-shaped section 1 including spaced parallel outwardly and downwardly diverging legs 2 and 3 and a crown portion 4 having a central depending bend 5. The crown portion functions as an axle or shaft for the floral supporting frame

generally designated by the reference character 6.

The third leg 7 is in the nature of a prop and has an eye 8 bent at its upper end to provide a pivotal connection with the bend or portion 5.

Between the legs 2 and 3 is a cross brace 9 having a flattened U-shaped keeper 10. I next call attention to a V-shaped stay element generally designated by the numeral 11 having its arm portion formed with eyes embracing the end portions of the cross brace 9 and having its apex portion bent to form a guide and retention loop as at 12 which embraces the adjustable prop or leg 7.

The aforesaid frame takes its form from a single length of wire bent upon itself into general rectangular form as shown. The intermediate portion of the sides thereof are formed with eyes as at 13 which embrace the part 4 and provide a pivotal or hinge mounting for the frame, allowing it to be swung to various adjusted positions with respect to the tripod. The lower end bar 14 has a centralized connecting portion 15 bent therefrom to afford a convenient connection for the retaining arm 16. The arm has its upper end formed with an eye which embraces this part 15 and the lower end portion of arm is flattened and provided with longitudinally spaced notches 17 to be selectively engaged with the keeper 10 in an obvious manner to change or regulate the angularity of the frame.

The free end portions of the wire forming the frame are bent into overlapping relationship as at 18 where they are coiled around as at 19 and 20 to form retaining spurs or fingers as at 21 and 22 respectively. The spurs are intended to be imbedded in the floral piece in an obvious manner to hold it securely in position on the frame and against displacement.

The following advantages accompany a structure of this type:

1. The adjustable position of the hinged frame makes it possible for one to adjust the display to the proper angle to more effectively show the wreath or spray attached.

2. The construction of the easel is such that

the entire display is elevated from the floor, mantle, table or wherever the same is placed, therefore it is shown to better effect.

3. The entire design may be shipped with 5 the easel attached, as the easel folds perfectly flat. The layman may thus set the entire display in the same position as the arrangement conceived by the artist. The simplicity of the invention makes it possible for any one 10 not familiar with the floral trade to properly use and adjust it.

4. My invention was conceived with the idea of supporting only one floral piece at 15 a time, while other racks and easels are so designed that they must be used for one large piece or many small pieces for undertaking parlors, etc.

5. Pots, pans and baskets may be securely held in the opening of the hinged frame and 20 may be thus used by the florist for decorating clubs, churches, etc.

6. When the hinged frame is set in place in a horizontal position, it assumes a flat plane which may be used as a table. This is 25 very handy to the floral trade, because the florist frequently is unable to find a suitable table to support his baskets, etc., while decorating.

From the foregoing description and drawing, 30 it will be seen that I have evolved and produced a simple and economical structure which is compact and convenient, and susceptible of fulfilling requirements of a structure of this class in a highly satisfactory and 35 efficient manner. It is thought that by carefully considering the description in connection with the drawing, the reader will be able to obtain a clear understanding of the invention and the features and advantages 40 thereof.

Therefore, a more lengthy description is regarded as unnecessary.

Minor changes in shape, size, and rearrangement of details may be resorted to in 45 actual practice if desired without departing from the spirit of the attached claims.

I claim:

1. In a structure of the class described, a foldable and adjustable supporting tripod 50 comprising a U-shaped member including spaced legs, a horizontal crosspiece connected to the intermediate portions of said legs, a substantially V-shaped stay device having its arm portions pivotally connected with said crosspiece, a prop pivotally connected at its upper end to the crown portion of said U-shaped member, the apex portion of said V-shaped stay being constructed for slidable engagement with said prop, and a floral piece 55 supporting frame hingedly mounted on the crown portion of said U-shaped member.

2. In a structure of the class described, a foldable and adjustable supporting tripod 60 comprising a U-shaped member including spaced legs, a crosspiece connected to the

intermediate portions of said legs, a substantially V-shaped stay device having its arm portions pivotally connected with said crosspiece, a prop pivotally connected at its upper end to the crown portion of said U-shaped member, the apex portion of said V-shaped stay being constructed for slidable engagement with said prop, and a floral piece supporting frame hingedly mounted on the crown portion of said U-shaped member, said crosspiece being formed intermediate its ends with a U-shaped keeper, a retaining arm pivotally connected at its upper end to the lower frame bar of said frame, said arm having its lower end flattened for slidable reception in 70 said keeper, said flattened end portion being provided with longitudinally spaced notches for selective engagement with said keeper.

3. In a floral rack of the class described, a foldable and adjustable support, a substantially rectangular floral supporting frame hingedly mounted between its ends on the upper portion of said support, adjustable retaining means for said frame, said frame being provided at its top with spaced retaining spurs.

4. In a floral rack of the class described, a foldable and adjustable support, a substantially rectangular floral supporting frame hingedly mounted between its ends on the upper portion of said support, adjustable retaining means for said frame, said frame being provided at its top with spaced retaining spurs, said frame being formed from a single length of wire bent upon itself to provide said spurs and provide hinge eyes for hinged connection with said support.

5. In a floral rack of the class described, an adjustable tripod comprising a U-shaped member, a prop hingedly connected at its upper end to the crown portion of said U-shaped member, retaining and bracing means for said prop and the leg portions of said U-shaped member, said means including a keeper, a substantially rectangular frame formed from a single length of wire, the side portions thereof being formed with hinge eyes hingedly connected with the crown portion of said U-shaped member, and a retaining arm pivotally connected to the lower frame bar and provided with longitudinally spaced retaining notches for selective engagement with said keeper.

In testimony whereof I affix my signature.

JOHN G. TURNER.
